UNITED STATES PATENT OFFICE.

ALLYN B. McINTIRE, OF NEWTON CENTER, MASSACHUSETTS, ASSIGNOR TO PEPPERELL MANUFACTURING COMPANY, OF BOSTON, MASSACHUSETTS, A CORPORATION OF MASSACHUSETTS.

DESIGN FOR A BOX COVER.

Application filed January 14, 1928. Serial No. 24,869. Term of patent 14 years.

To all whom it may concern:

Be it known that I, ALLYN B. McINTIRE, a citizen of the United States of America, and a resident of Newton Center, in the county of Middlesex, State of Massachusetts, have invented a new, original, and ornamental Design for a Box Cover, of which the following is a specification, reference being had to the accompanying drawing, forming part thereof.

In the drawing:

Figures 2 and 3 are oppositely disposed end views of the same cover, showing continuity of the design.

I claim:

The ornamental design for a box cover as shown and described.

ALLYN B. McINTIRE.
